UNITED STATES PATENT OFFICE.

FREEBORN F. RAYMOND, 2d, OF NEWTON, MASSACHUSETTS.

BUTTONHOLE-SEWING MACHINE.

SPECIFICATION forming part of Letters Patent No. 588,353, dated August 17, 1897.

Application filed July 18, 1892. Serial No. 440,399. (No model.)

To all whom it may concern:

Be it known that I, FREEBORN F. RAYMOND, 2d, a citizen of the United States, residing at Newton, in the county of Middlesex, in 5 the State of Massachusetts, have invented a new and useful Improvement in Buttonhole-Stitching Machines, of which the following is a full, clear, and exact description, reference being had to the accompanying drawings, 10 forming a part of this specification, in explaining its nature.

The invention relates to an organized buttonhole-stitching mechanism in which the buttonhole-clamps and clamp plate or plates 15 are moved from stitching position to an anvil and cutter which are actuated while the clamps are in operative relation thereto, and which clamps and clamp plate or plates are then returned to their normal position and 20 held stationary, while the stitching devices are caused to travel around the edge of the buttonhole.

The object of the invention is to provide an organization which shall permit both the rapid 25 slitting of the buttonhole and the rapid stitching of its edges by devices which coöperate but are independently actuated.

The invention is in some respects an improvement upon those described in the House 30 and House patents of 1863 and the Reece patents, Nos. 240,546 and 349,359.

The House and House patents describe a buttonhole-sewing machine in which the stitching devices are movable about the edges 35 of the stationarily-held buttonhole-slit, but there is no description of a means for slitting the buttonhole.

The Reece patents describe a machine which follows the lines of the House and 40 House description in that the material is held stationary and the stitching devices moved about the buttonhole-slit and which has in addition an anvil and buttonhole-cutter which are mounted upon the frame carrying the 45 stitching devices and which are moved to the stationarily-held fabric, actuated to cut the buttonhole slit therein, and then moved from it to bring the stitching devices into operative relation to the said slit.

50 The same mechanism which is used for intermittently moving the stitching devices around the buttonhole-slit is also employed in

moving the cutter and anvil into and out of operative position, and it requires very nearly, if not quite, as much time to move the buttonhole-cutting devices into and out of operative position and to operate them as it does to stitch the buttonhole. 55

The mechanism in the Reece machine for giving movements to the cutter and anvil and the stitching devices comprises a cam-disk having two cam-grooves, one of which revolves around a stationary cam-pin and both of which are connected with the frame carrying the cutting and stitching devices. There is also 60 in the Reece machine no provision for returning the stitching devices after the stitching of the buttonhole to their original position excepting that derived from the continued movement of the frame-feed cams after the 65 stitching has been completed.

My invention differs from the Reece in that the stitching devices and their supporting-framework are not moved except to stitch the edge of the buttonhole, in that the buttonhole-slitting devices are not carried by the frame which carries the stitching devices, in that no additional movement of the frame or frame-feeding devices after the stitching of the buttonhole is needed for restoring the 75 stitching devices to their original position, and in that the clamp-plate and clamp are by a continuous and rapid movement fed to and from stationary buttonhole-cutting mechanism by devices entirely independent 80 of the stitching devices or frame-feeding mechanism and before they are started.

One of the practical advantages of my invention as compared with the House and House machine is that the automatic buttonhole-cutting devices are organized into the machine without requiring but a little more time for their operation, and one of the advantages of my invention as compared with the Reece is that by disassociating the buttonhole-slitting mechanism from the stitching devices and not requiring a further operation of the feeding-cams to restore the stitching devices to their normal position at the end of the stitching of the buttonhole a 90 very considerable saving in the time of the operations of slitting and stitching is accomplished, and by said disassociation and by giving the frame carrying the stitching de- 95 100

VICES A SHORTER THROW A STIFFER, STRONGER, AND BETTER CONSTRUCTION IS OBTAINED.

The invention relates to various other features of organization and construction, which 5 will hereinafter be fully described.

Referring to the drawings, Figure 1 is a view in side elevation of a machine having the features of my invention. Fig. 2 is a view in horizontal section substantially upon a line 10 with the cutter-lever and in plan of parts below said line. Fig. 3 is a view principally in elevation to illustrate the starting mechanism. Fig. 4 is a view of one of the feed-cams to which reference is hereinafter made. Fig. 15 Fig. 5 is a view showing the mechanism for returning the stitching devices at the end of the stitching operation and of the movement of the frame to their normal position. Fig. 6 is a view in section showing the clutch mechanism 20 of the stitching devices to which reference is hereinafter made. Fig. 7 is a plan view of the bed of the machine without any of the parts mounted on it. Fig. 8 is a plan view of the bed, showing certain parts mounted 25 on it, some of these parts being broken away in horizontal section. Fig. 9 is a plan view of the cam-disk for feeding the stitching mechanism.

A is the bed of the machine. It is stationary. It has at its forward end guideways a for directing the movement of a slide-plate A' . This slide-plate carries the clamps A^2 A^3 , which preferably are mounted upon the separable clamp-plates A^4 A^5 , the clamp-30 plates being pivoted at a' a^2 , respectively, to the slide-plate A' . The stationary bed A has at its center and rear end a slideway b for the frame B. This frame has the upperarm B' and the lower arm B². These arms carry 35 the stitching devices B³ B⁴ and the frame B, and the stitching devices are like those described in the Reece patents above referred to (with the exception hereinafter noted) and shown in the Reece machine and need not 40 further be described here.

The frame B is provided with its traveling or feed movement by the cams b' (see Fig. 4) and b^2 in the cam-disk B^5 . The cam-disk is mounted upon the central bearing-post b^3 of 45 the frame and moves with the frame, the cam b' engaging the stationary cam-pin b^4 , which is attached or secured to the cross-bar b^5 of the stationary bed. The cam b^2 is connected with the frame B through the lever b^3 , as described in said Reece patents, and 55 the traveling frame is adapted to be swung on its pivot b^4 by said cam, as therein specified, to give the stitching mechanism a proper lateral movement about the eye of a button-hole. There is, however, this distinction between the cam-disk B^5 and its cams and the cam-disk and cams of the Reece patents: The cam-disk B^5 is directly connected with the main shaft C of the stitching-machine, to 60 be operated by it only when it is started, and not with an eccentric upon a constantly-rotating hub of the driving member of a clutch.

The cam-disk also makes its full revolution during the stitching operation, using no part of its time for the cutting operation. Consequently the cam-disk has fewer feeding-teeth and the cam b' shorter travel, its travel being limited to move the framework and stitching devices only the length of a buttonhole and not about twice the length of a buttonhole, as is necessary when it is employed for moving the buttonhole-cutting mechanism into and out of position and the stitching devices back and to their normal position. The cam b^2 is also modified slightly to meet the decreased throw of the frame and stitching devices and the conditions incidental thereto.

The cam-disk is intermittently rotated by the eccentric c on the main shaft C of the stitching mechanism and the lever c' , which acts to reciprocate the cam-disk clutch in the same manner as described in said Reece patents, the difference in the clutch mechanism being that the devices which serve to throw it into and out of operation, not being needed, are not employed, the clutch being actuated by its lever c' only during the rotation of the shaft C and having no connection with the operation of the buttonhole-cutting devices.

The clamps A^2 A^3 are depressed upon the work and clamp-plates by the movement of the starting-lever D. This lever and the mechanism connecting it with the clamps and the mechanism for automatically releasing the clamps at the end of the stitching of the buttonhole are like those described in the Reece patent No. 349,359 and need not further be described here, excepting that the clamp-closing arms, depressed by the lever D, are pivoted to the slide-plate A' instead of to the stationary bed of the machine, as in the said Reece patent.

The buttonhole-cutter E is not attached to the frame B to move with it, but is pivoted at e to stationary ears e' , rising from the stationary bed A, and is provided with a movement toward and from the stationary anvil E' by means of the cam E^2 upon the independent and non-traveling shaft F. This shaft is supported, preferably, by stationary supports rising from the bed A, and it has at one end the driven member F' of a clutch fastened to it and the driving member F², which is loose upon it and which is adapted to engage the member F' at the will of the operator and impart to it one revolution.

The plate A' carrying the clamps and clamp-plates is moved from a position in operative relation with the stitching devices to a position over the anvil and below the cutter E by means of the draw-cam A⁶ on the shaft F, and the draw-bar a^3 and the slide-plate, clamps, and clamp-plates are returned after the drawing action of the cam A⁶ and the operation of the cutter to their original position by the springs a^4 . The clamp-plates A⁴ A⁵ are spread after the buttonhole-slit has been cut, but before they have been returned to their stitching position, by the tapering spreader G, which

is carried at the end of the push-bar g and which is actuated by the cam G' on the shaft F to be moved or pushed between the two plates $A^4 A^5$ immediately before the cam A^6 releases the slide A' to permit of its quick return. A spring g' serves to return the spreader G to its original position after the operation of the cam G' .

From what has been stated it will be seen that the first operation of the machine is to close by the movement of the lever D the clamps upon the fabric held by the clamp-plates. This movement instantly sets in operation the shaft F , the lever D being connected with the clutch, as will hereinafter be specified. The clamps, clamp-plates, and slide A' are instantly moved to cutting position, the cutter actuated, the clamps spread, and the clamped fabric, clamp-plate, and slide returned to their stitching position—that is, to a stationary position in relation to the stitching devices, which are then caused to travel about the edge of the buttonhole-slit—in which position they remain at rest during this subsequent stitching of the buttonhole. The instant they resume this position the buttonhole-stitching devices are set in operation and the cam-disk B^5 for the first time operated and the forward end or ends of the frame B caused to travel about the edge of the buttonhole-slit, the shaft F making but one revolution and then automatically stopping, and at the end of its revolution communicating, through mechanism to be described, to the stitching-machine shaft-clutch a starting movement.

The shaft F is started by withdrawing the latch H from the spring-actuated engaging lug h . This permits the lug to be engaged by a projection on the driving member and a revolution of the shaft F to be made. The lug or tooth is disengaged at the end of one revolution by the return of the latch H to original or normal position. The latch projects inward from the upper end of the bar h' . (See Fig. 3.) The slide-bar has at its forward end the shoulder or tooth h^2 and the upward extension or fulcrum-point h^3 . The trip or starting lever D has a long pawl h^4 , pivoted at h^5 , held in contact with the stop h^6 by a spring h^7 . When this trip or lever D is moved from the position represented in Fig. 3 to that represented by dotted outlines in the same figure, its first action is to throw downward the clamps $A^2 A^3$. Its continued movement brings the end of the pawl into engagement with the tooth h^2 and causes the slide h to be moved sufficiently to disengage the latch H from the lug h . Further movement of the slide h causes the pawl h^4 to be lifted from the tooth h^2 by the under surface of the pawl riding upon the fulcrum-point h^3 , the center or pivot point h^5 of the pawl lowering as the lever is moved sufficiently to cause the end of the pawl to be lifted or pried from the tooth, and this permits the spring h^7 to move the slide back-

ward regardless of the position of the starting-pawl h^4 and of the position of the lever D , as upon the lifting of the end of the pawl h^4 the tooth h^2 will be immediately moved backward under it, so that it cannot be again engaged by the pawl until the trip-lever has been returned to its normal position.

The clutch of the shaft of the sewing or stitching mechanism is like that of Patent No. 349,359. It has the driving member C' and the driven member C^2 , and the lever-arm K and engaging dog K' are caused to be actuated by the lever K^2 instead of by the controlling-bar, as described in said patent. This lever K^2 is pivoted at k and has the short arm k' , which extends into the path of the starting-cam k^3 on the shaft F . The long arm k^3 of the lever extends under the adjusting-screw k^4 of the starting-lever K , and when the shaft F has about completed its rotation the cam k^3 moves the lever K^2 , causing it to act through the lever K to disengage the dog and permit the engagement of the two clutch members $C' C^2$ and thus start the stitching-machine shaft, the dog being held removed from the members of the clutch sufficiently to permit the end of the adjusting-screw k^4 to pass upon the raised surface k^5 of the controlling-lever K^2 .

It will be understood, of course, that upon the engagement of the member $C' C^2$ of the sewing mechanism C the frame B is immediately moved, and the screw is thus brought over the raised section k^5 of the controlling-lever, and the dog is thus maintained disengaged from the clutch so long as the frame moves forward and backward until it has sewed the last stitch of the buttonhole, when the screw rides off the raised section k^5 , and the dog is brought into a position between the two members of the clutch and the further engagement of the two stopped.

The clamps $A^2 A^3$ are released automatically at the stopping of the stitching mechanism as described in the said Patent No. 349,359. As the movement of the frame B and of the stitching devices longitudinally stops at the completion of the stitching of the last side of the buttonhole, and as the feed-cams also then stop, it becomes necessary to return the stitch-forming mechanism—namely, the needle-bars and loopers—to their original position by other means than the cam employed in rotating them while stitching about the eye.

The mechanism turning the stitching devices in sewing about the eye is similar to that described in the said Patent No. 349,359. It comprises the pinions $L L'$ on the upper and lower needle-bars, respectively, the sections $L^2 L^3$, which respectively engage said pinions and are connected by the bar L^4 , (see Figs. 1 and 5,) and the cam groove or path L^5 in the cam-disk B^5 . This cam-groove has the rest l , the operative run or section l' , and the rest l'' , which terminates in the radial section l^3 , connecting the end of the rest l'' with

the end of the rest l . This radial section l^3 of the cam comes into line with the cam-pin l^4 of one of the sector-levers at the instant the buttonhole-stitching mechanism has sewed 5 the last stitch and its shaft has come to rest, and the spring l^5 , connected with the sector-lever to act upon it, then serves to move the sector-levers backward to their original position and the cam-pin from the end of the rest 10 l to the beginning of the rest l^2 , and at the same time rotating the needles and looping mechanism backward to their original position.

The cams B^5 L^5 are formed in a common 15 disk, one in the upper surface and the other in the lower surface thereof, and it is supported upon a pivot or stud attached to the moving frame. It may be turned in any desired way. That which is described and illustrated 20 is like a similar mechanism described in the said Patent No. 349,359, it being understood that the disk has by these means an intermittent rotation given it.

The operation of the machine is as follows: 25 The fabric having been placed between the clamps and clamp-plates, the operator moves backward the starting-lever D , and by this action closes the clamp upon the fabric and against the clamp-plates and permits the engagement 30 of the two members and the clutch of the shaft F , whereby it is set in operation and caused to make one revolution and stop. The movement of this shaft causes the clamps, clamp-plates, and clamp-plate slide to be 35 drawn from their stitching position to a position which brings the material between the clamps underneath the buttonhole-cutter and over the anvil. The cutter is immediately actuated to cut the buttonhole-slit, the clamps 40 are spread to open the buttonhole-slit, and the clamped material, clamps, clamp-plates, and slide are instantly returned to their stitching position, where they remain stationary during the subsequent stitching of the buttonhole. 45 The buttonhole-stitching devices and mechanism are immediately and automatically set in operation and are moved with an intermittent feed movement about the edge of the buttonhole-slit around the eye and backward 50 upon the other side of the slit, the stitching devices rotating during the movement around the eye, when the sewing mechanism and feed-frame automatically come to rest and the needles and loopers are automatically 55 released and returned.

It will be seen that the movement of the clamps, clamp-plates, &c., from the stitching position to the cutter is a continuous and quick one, and that the return is also continuous and quick, and that the whole movement to the cutter and back is accomplished in the time of one rotation of the shaft F , and that this shaft can be run at any desired speed, and that consequently the movements 60 of the clamps, &c., to the cutter, the operation of the cutter, and the return movement of the clamps is a very quick operation com-

pared with the step-by-step feeding movement of the frame B in stitching.

It will also be seen that the frame B and 70 stitching devices are moved only during the stitching of the buttonhole and only for the length of such buttonhole.

I would say that the stitching devices, so far as the needle and looper and their actuating 75 device are concerned, may be like those of the "Globe" machine, and described in Reed and Dahl patents, Nos. 450,844 and 450,950.

Having thus fully described my invention, I claim and desire to secure by Letters Patent of the United States—

1. In a buttonhole-stitching machine, the combination with the stationary bed of the machine provided with two slideways, of a traveling frame movable back and forth on 85 one of said slideways, a buttonhole-stitching mechanism carried by said traveling frame, means for causing said frame to travel back and forth to carry the said stitching mechanism about a buttonhole-slit, a clamping 90 work-holding device movable in the other of said slideways, a buttonhole-cutting mechanism which is stationary relative to the said traveling frame, means for moving the said clamping work-holding device to the cutter 95 of the said buttonhole-cutting mechanism when a buttonhole is to be cut and for returning said clamping work-holding device to its normal position, where it will remain stationary until the next buttonhole is to 10 be cut, and connecting mechanism, whereby when the machine is started the clamping work-holding device will first be moved to the buttonhole-cutter and then instantly returned to its initial position and remain stationary while the buttonhole-stitching mechanism will be caused to travel about a buttonhole-slit to stitch the buttonhole, substantially as set forth.

2. The combination in a buttonhole-stitching machine of the bed-plate of the machine, a frame carrying the stitching devices at its forward end or ends, movable upon such bed, a cam-disk having a step-by-step rotation imparted to it, cams in said disk connected 11 with said frame and constructed to move the same only the length of the buttonhole to be stitched, and to carry the stitching mechanism about the eye of the buttonhole, means for rotating the stitching devices a half-revolution during the stitching of the eye, and for holding them against rotation during the stitching of the sides of the buttonhole, including the cam L^5 in the cam-disk, constructed to permit the immediate movement 12 of the mechanism for rotating the stitching devices at the end of the stitching of the last side of the buttonhole, and a spring connected with said mechanism to actuate it at the end of the stitching operation to turn 13 back the stitching devices to their original position, substantially as and for the purposes described.

3. In a buttonhole-stitching machine, the

combination with a stationary bed, of work-clamps supported by said bed, a traveling frame mounted on said bed, stitch-forming devices carried by said traveling frame, the 5 traveling-frame-actuating cams also carried by said traveling frame, the disk B⁵ provided with the cam-groove L⁵ connected with said stitch-forming devices and having the rests l and l', the operative section l' and the release-section l'', and means for returning said stitch-forming devices to their initial positions, substantially as described.

4. In a buttonhole-stitching machine, the combination with the stationary bed of the 15 machine, the traveling frame mounted thereon, the stitch-forming devices carried by said frame and movable therewith, the shaft C provided with means for actuating the said stitch-forming devices, the eccentric c on said 20 shaft, the cam-disk having cams connected with said frame and constructed, as specified, to move it only the length of the buttonhole to be stitched, a cam constructed, as specified, to rotate the stitch-forming devices in one direction only, means for returning said stitch-forming devices to their initial position, a clutch to engage the said cam-disk, and an intermediate-clutch-actuating lever operated 25 by said eccentric, and members of a clutch 30 upon the said shaft C, all constructed and arranged, as specified; whereby upon the engagement of these members of the clutch the said shaft is actuated and the stitch-forming devices and the cam-disk, or frame-moving 35 mechanism, simultaneously started, as and for the purposes described.

5. In a buttonhole-stitching machine, the combination with the stationary bed of the machine provided with two slideways, of a 40 traveling frame movable back and forth on one of said slideways, a buttonhole-stitching mechanism carried by said traveling frame, means for causing said frame to travel back and forth to carry the said stitching mechanism about a buttonhole-slit, a clamping work-holding device movable in the other of said 45 slideways, a buttonhole-cutting device mounted on said stationary bed of the machine, start and stop motion mechanism for said 50 shaft and devices on said shaft connected with the clamping work-holding device and buttonhole-cutting mechanism and serving to move the said work-holding device to the cutting mechanism and to actuate the said cutting 55 mechanism to form a slit in the material held by the clamp and to separate the members of the clamps, and means for returning the said clamping work-holding device to stitching position after a buttonhole has been cut.

6. In a buttonhole-stitching machine, the combination with the stationary bed of the machine provided with two slideways, of a 60 traveling frame movable back and forth on one of said slideways, buttonhole-stitch-forming devices carried by said traveling

frame, the shaft C mounted in said traveling frame and provided with means for operating said stitch-forming devices, start and stop motion mechanism for said shaft, means for causing said frame to travel back and forth to carry the said stitch-forming devices about a buttonhole-slit, a normally stationary work-holding device movable in the other of said slideways, buttonhole-cutting devices fixedly mounted upon said stationary bed, 70 the shaft F also mounted upon said stationary bed, start and stop motion mechanism for the said shaft F, and means, carried by the said shaft F, for moving the said work-holding device to the buttonhole-cutter and 80 for operating said cutter, and means for returning the said work-holding device to its initial or stitching position; whereby when the machine is started the work-holding device will be moved to the buttonhole-cutter, 85 a buttonhole-slit cut, said work-holding device be instantly returned to stitching position, the said stitch-forming devices then be set in operation and caused to travel about the stationary buttonhole-slit for the purpose 90 of working a buttonhole and the machine then be automatically stopped, substantially as described.

7. In a buttonhole-stitching machine, the combination with the stationary bed of the 95 machine provided with two slideways, of a traveling frame movable back and forth on one of said slideways, a buttonhole-stitching mechanism carried by said traveling frame, means for causing the said frame to travel 100 back and forth to carry the said stitching mechanism about a buttonhole-slit, a clamping work-holding device movable in the other of said slideways, a buttonhole-cutting mechanism which is stationary relative to the said 105 traveling frame, means for moving the said clamping work-holding device to the cutter of said cutting mechanism when a buttonhole is to be cut and for returning said clamping work-holding device to its initial position, 110 the said buttonhole-stitching mechanism and the said buttonhole-cutting mechanism being independent of each other, and the latter being stationary relative to the former, and means for successively operating the said 115 mechanisms so that when the said cutting mechanism is in operation the said stitching mechanism will be at rest, and vice versa; whereby when the machine is set in operation the work will be quickly moved to the 120 buttonhole-cutter, the buttonhole cut, the work instantly returned to its normal stationary position and the said stitch-forming mechanism then be set in operation and be caused to travel about the buttonhole-slit to 125 work the buttonhole.
